Patented July 29, 1919.

UNITED STATES PATENT OFFICE.

RICHARD M. HOPKINS, OF RUTHERFORD, NEW JERSEY, ASSIGNOR TO AMERICAN DISTRICT TELEGRAPH COMPANY, OF JERSEY CITY, NEW JERSEY, A CORPORATION OF NEW JERSEY.

SIGNALING SYSTEM.

1,311,649.

Specification of Letters Patent. Patented July 29, 1919.

Application filed March 13, 1918. Serial No. 222,078.

To all whom it may concern:

Be it known that I, RICHARD M. HOPKINS, a citizen of the United States of America, and a resident of Rutherford, in the county 5 of Bergen and State of New Jersey, have invented certain new and useful Signaling Systems, of which the following is a specification.

My invention relates generally to signaling systems, and particularly to systems wherein one or more call boxes, thermostats, burglar alarms, or other transmitting devices are to cause the operation of signal giving devices in a plurality of circuits. 10 The system is particularly applicable to fire alarm systems of large stores, warehouses, etc., wherein, in the event of fire, alarms are to be sounded at a large number of different points. In such systems, it is 15 usually desirable that only a relatively small number of alarm giving devices shall be located in any one circuit; hence the occasion for the provision of a plurality of circuits for such alarm giving devices. It is desirable 20 that the circuits shall be constantly under test, so that in case of any derangement (such for example as breaking of the circuit, or grounding of the circuit) a trouble signal shall be given; yet in case an alarm 25 signal is sounded, the several circuits of the alarm giving devices should be connected separately to the source of current supply; so 30 that derangement of one such circuit shall not prevent operation of the other circuits, and so that there shall be ample current in 35 each circuit for the operation of the alarm giving device thereof.

My system herein illustrated and described is particularly intended to be used in 40 connection with signal giving devices which require relatively strong currents for their operation, as compared with the currents required for electric bells and the like, so that it is desirable that the supply of current to 45 such signal giving devices shall be controlled by relays of a type adaptable for the handling of moderately large currents, and of a type which, for various reasons, it is not desirable to include directly in the transmitter circuit itself. Furthermore, the system herein described is particularly intended for use where the current designed 50 to operate the signal giving devices is to differ, either as to character or as to voltage, from the current designed to be used 55

for the immediate operation of the means whereby such alarm giving devices are controlled and the various circuits supervised. For example, the current whereby the alarm giving devices are to be operated may be an 60 alternating current, whereas the current to be used for the operation of the instruments by which that alternating current is controlled, and by which supervision is effected, 65 may be direct current of low voltage.

The objects of my invention are to provide a suitable signal system for the operation of one or more signal giving circuits containing signal giving devices requiring an operating current of somewhat greater 70 strength than that ordinarily required by electric bells and the like, and to provide for the automatic continuous testing of the signal giving circuits in a simple manner and by means of relatively small testing 75 currents, also to provide for the operation of the instruments by which the main signal giving current is controlled, and by which testing is effected by a current of a character or of a voltage different from that of the 80 signal giving current.

I will now proceed to describe my invention with reference to the accompanying drawing, which illustrates, more or less diagrammatically, a system embodying my invention, and will then point out the novel 85 features in claims.

In the drawings: V and G represent respectively incoming and outgoing current leads for the main or signal giving current. 90 B designates an immediate source of current for the operation of the instruments and for the supply of current for testing purposes; which source B may be, for example, a storage battery, arranged to be charged from 95 time to time from an alternating source of supply X-Y through a charging rectifier R. A designates magnet spools of a direct current relay and a the armature of that relay, and H designates a delay action relay 100 of familiar type, having contacts S¹ and S² arranged to be operated by an armature extension of relay H; contact S¹ being normally closed and contact S² being normally open. C designates a relay (for example, a 105 relay of the solenoid type), controlling the various alarm giving circuits, as hereinafter described. T¹ is a circuit containing various signal boxes or transmitters T, and F¹, F², F³, and F⁴ are circuits containing va- 110

rious alarm giving devices, for example, alternating current horns, F. M is an ammeter relay, viz., a combined ammeter and relay, of well known character.

5 The circuits of the system are as follows: from one pole of battery B through conductor 1 to a milli-ammeter M² and thence through conductor 2 and the coils of retard relay H and conductor 3 to transmitter circuit T¹ and thence through conductor 4 and the coils of relay A and thence through conductor 5, back to the other pole of battery B. By this circuit the armature a of relay A is normally maintained in attracted position, and the armature h of retard relay H is normally maintained in the position shown. The circuit thus traced is maintained normally under supervision in the following manner: Should the circuit be 15 broken, or the battery current decrease greatly, the armature h of relay H will be permitted to drop, and contact S² will close, thereby closing a signal circuit from battery b through conductor 6, contact S², conductor 7, and a trouble signal bell 8 back to battery b.

Breaking of the circuit 1—5, (which breaking may be caused by the operation of one of the transmitters T,) causes the 30 dropping of armature a of relay A, whereby a circuit is completed from battery B through conductor 1—9 to the coil of solenoid relay C, conductor 10, and contact S¹ of relay H, and conductor 11 to the lower 35 contact of relay A, and thence through the armature of that relay (such armature being then retracted) and conductor 12 to conductor 5 and so back to battery. The energization of the magnet of relay C closes 40 the various contacts c¹ c¹, c² c², c³ c³, and c⁴ c⁴. Thereby the various signal giving circuits F¹, F², F³, and F⁴ are completed, as follows: from conductor V through fuse f² and relay contacts c³ and thence through 45 conductor 13, fuse f⁴ and conductor 14, circuit F² and conductor 15, and contacts c² to fuse f⁵ and thence to G; also by the path previously traced through conductor 14 to conductor 16 to contacts c⁴, fuse f¹ and thence to G; also from V 50 through fuse f² and contacts c¹, conductor 17 and fuse f⁵ to circuit F¹ and thence through conductor 15 and contacts c² to fuse f¹ and thence to G; also from V 55 through fuse f², fuse f³ and circuit F⁴ to conductor 16 and thence through contacts c⁴ to fuse F¹ and so to G. Ammeter relay M is normally included in the several circuits F¹, F², F³, F⁴ in series as follows: from 60 source G through fuse f¹ and a high resistance R¹ to said ammeter relay M and thence through conductor 18, fuse f⁵, circuit F¹, circuit F², circuit F³, and circuit F⁴ to fuse f³ and thence through fuse f² to V; but the 65 resistance R¹ is so high, that the sound

producing devices in these circuits F¹ to F⁴ are not operated by the current through M; but such current is nevertheless sufficient to cause said relay to hold open the circuit from battery b through conductor 19, the 70 contacts of said relay and conductor 20 to conductor 7, signal bell 8, and back to battery. By this circuit 19—20, the various circuits F¹, F², F³, and F⁴ are supervised, since, if any one of said circuits F¹—F⁴ be 75 opened, or grounded, the relay M will close the circuit 19—20, causing the bell 8 to sound.

During the operation of any one of the transmitters T, (which transmitters when 80 they operate will open and close the circuit T¹ according to some distinctive code signal, for example, a numeral), the consequent alternate deenergization and energization of relay A will cause the signal giving 85 devices in all of the circuits F¹—F⁴, to operate, sounding the signal of the particular box T which has been operated and, correspondingly, the trouble signal bell 8 will also sound such signal. It is not desired, 90 however, that in case of a break in the circuit T¹, produced otherwise than by the operation of the signal boxes T, the signal giving devices F shall continue to operate; therefore, in case of continued break in the 95 circuit T, the armature of relay H drops far enough to open the contact S¹ of that relay, so deenergizing the magnet of relay C and breaking the circuits F¹—F⁴ at the contact points of this relay C. But in this 100 event the bell 8 will continue to ring until the break in the circuit T¹ has been repaired.

It will be noted that the circuit by which 105 relays A, H, and C are controlled is entirely separate, both as to source of energy, and as to connections, from the circuit from current supply V, G, to the various circuits F¹—F⁴. The system is, therefore, adapted to conditions whether a high potential current or an alternating current is desired for 110 the operation of the signal giving devices F, while a current of different character or potential, for example, a low potential direct current, is desired for operating the instruments.

M¹ is a voltmeter bridged across the circuit 1—5 for indicating the voltage in that circuit.

The invention of this application embodies in part the invention of my prior 120 application, Serial No. 126,649, filed October 20, 1916, and embodies a modification of the invention of said prior application.

What I claim is:

1. In a signaling system the combination 125 of a transmitter circuit comprising one or more transmitters, a signal giving circuit entirely separate from said transmitter circuit and comprising one or more signal giving devices, independent sources of current 130

- supply for said two circuits, a main controlling relay and a delay action relay in said transmitter circuit, a further relay and a circuit therefor, said further relay controlling the signal giving circuit and controlled through its circuit by said main relay and arranged when operated by said main relay to close the signal giving circuit, said delay action relay having contacts arranged to break the circuit of said further relay in the event of prolonged breakage of the transmitter circuit.
2. In a signaling system the combination of a transmitter circuit comprising one or more transmitters, a signal giving circuit entirely separate from said transmitter circuit and comprising one or more signal giving devices, independent sources of current supply for said two circuits, a main controlling relay and a delay action relay in said transmitter circuit, a further relay and a circuit therefor, said further relay controlling the signal giving circuit and controlled through its circuit by said main relay and arranged when operated by said main relay to close the signal giving circuit, said delay action relay having contacts arranged to break the circuit of said further relay in the event of prolonged breakage of the transmitter circuit, and a trouble signal device and circuit therefor controlled by a further contact of said delay action relay, and arranged to be operated by said delay action relay in the event of breakage in the transmitter circuit.
3. In a signaling system, the combination of a transmitter circuit comprising one or more transmitters, a plurality of signal giving circuits entirely separate from said transmitter circuit and each comprising one or more signal giving devices, independent sources of current supply for said transmitter circuit and for said signal giving circuits, a main controlling relay and a delay action relay in said transmitter circuit, a further relay and a circuit therefor con-
- trolled through its circuit by said main relay and arranged when operated by said main relay to close the signal giving circuits, said delay action relay having contacts arranged to break the circuit of said further relay in the event of prolonged breakage of the transmitter circuit, said signal giving circuits being connected in multiple to their respective source of supply through normally open contacts of said further relay, and a high resistance test circuit connecting said signal giving circuits in series, and a test relay in such test circuit.
4. In a signaling system, the combination of a transmitter circuit comprising one or more transmitters, a plurality of signal giving circuits entirely separate from said transmitter circuit and each comprising one or more signal giving devices, independent sources of current supply for said transmitter circuit and for said signal giving circuits, a main controlling relay and a delay action relay in said transmitter circuit, a further relay and a circuit therefor controlled through its circuit by said main relay and arranged when operated by said main relay to close the signal giving circuits, said delay action relay having contacts arranged to break the circuit of said further relay in the event of prolonged breakage of the transmitter circuit, said signal giving circuits being connected in multiple to their respective source of supply through normally open contacts of said further relay, and a high resistance test circuit connecting said signal giving circuits in series, and a test relay in such test circuit.

In testimony whereof I have signed this specification in the presence of two subscribing witnesses.

RICHARD M. HOPKINS.
